UNITED STATES PATENT OFFICE.

CLYDE L. MICHAEL AND HENRY KELL, OF AURORA, ILLINOIS.

WINDOW-SHADE MACHINE.

1,198,368.

Specification of Letters Patent. Patented Sept. 12, 1916.

Application filed April 2, 1914. Serial No. 329,128.

To all whom it may concern:

Be it known that we, CLYDE L. MICHAEL and HENRY KELL, citizens of the United States of America, and residents of Aurora, 5 county of Kane, and State of Illinois, have invented certain new and useful Improvements in Window-Shade Machines, of which the following is a specification.

This invention relates to machines 10 adapted for handling cloth, paper, or similar material in the process of cutting and forming the same into desired shapes in manufacturing processes, and more particularly to feed, cut, fold and sew the cloth 15 and attach same to rollers in the process of manufacturing window-shades.

The main objects of this invention are to provide an improved form of machine adapted to perform automatically or mainly 20 so the successive steps in the process of manufacturing window-shades complete; to provide a gage adapted and connected to measure the length of material used in the shades; to provide means for gaging the 25 width of the shades and means for trimming the edges thereof; to provide convenient means for fastening one end of the cloth to the shade-roller; to provide automatic means for creasing the opposite end 30 to facilitate folding to form a pocket for the shade-stick; to provide means for sewing the edge or edges of said pocket; and to provide automatic cut-off means adapted and arranged for severing the successive 35 lengths of shade material from the supply roll simultaneously with the creasing operation.

An illustrative embodiment of this invention is shown in the accompanying drawings, in which—

Figure 1 is an end elevation of the shade machine, the gearing being represented diagrammatically. Fig. 2 is a front elevation of the machine. Fig. 3 is a bottom plan 45 view of the driving and controlling mechanism of the sewing attachment. Fig. 4 is an enlarged cross section illustrating a modified form of creaser bed-plate and coacting roll. Fig. 5 is a cross section at A—A on Fig. 3 of the threaded clutch and its release screw by which the sewing machine is controlled. Fig. 6 is an axial section of one of the lateral gage trimmers and associated members. Fig. 7 is a cross section of the 50 creased end of a one-color shade partly

folded. Fig. 8 shows the device of Fig. 7 folded and sewed, and with the shade-stick in place. Fig. 9 is a cross-section of the creased end of a two-color or "duplex" shade partly folded. Fig. 10 shows the device of 60 Fig. 9 folded and sewed and with the shade-stick in place. Fig. 11 is a fragmentary view of one of the cutter supporting brackets and supporting frame therefor, the frame being in cross section. Fig. 12 is a 65 cross-section of the winding roller which drives the shade roller.

In the construction shown in the drawings the mechanism is carried by a frame 1 comprising a pair of end brackets or plates 2 and 3 and rigid connecting means preferably in the form of bars secured to said plates. One of said bars 4 serves as a stiffener for the frame, and supports certain parts of the device, a second bar 4' is formed 70 and adapted to serve as a bed-plate for the creasing and folding mechanism 5, and another of said bars 6 is formed and adapted to serve as a guide and support for the sewing or stitching apparatus 7.

A pivot rod 8 is disposed longitudinally of the machine, preferably at the lower rear portion of the machine for receiving and supporting a supply roll or bolt 9 from which the cloth 10 is fed for making the 85 window-shades. A feed roll 13 is provided to which power is applied, and over which the cloth passes on its way to the cut-off and folding mechanism 5. Adjacent to said feed roll is another feed roll 14 carried by movable brackets 15 which are pivoted to the frame at points 16, whereby roll 14 may be thrown into and out of coactive rolling engagement with roll 13, said rolls being adapted and arranged for the cloth to feed 90 between, and roll 13 preferably being rubber-covered to more definitely grip the cloth.

A measuring means, preferably in the form of a visual recording gage 18, comprising a dial and hand is operatively connected to roll 14, whereby the cloth may be measured as it is fed forward, a worm gear connection being shown in Figs. 1 and 2.

Any convenient means may be provided for driving roll 13, but in the form shown 105 manually operated means are provided comprising a gear wheel 20 journaled on the frame plate 2 and having a crank 21 for driving the same, said wheel being arranged to coact with a gear wheel 22 carried on the 110

adjacent end of the feed roll 13. Preferably a flange 25 is provided on the frame plate whereby the plate is strengthened and the gearing protected. Another roll 26 adapted for drawing the shade cloth forward and winding same on the shade-roller 27 is operatively connected to the driving gear 20, the connection in this instance comprising a gear wheel 28 carried by said roll and an idle-wheel 29 connecting therefrom to the driving gear 20. Means 30 are provided adjacent to the roll 26 for holding the shade-roller 27 upon which the shade is rolled, said supporting means being adjustable and adapted and arranged for causing said shade-roller to bear coactively upon the roll 26, whereby the cloth of a suitable length for the shade may be wound directly upon its roller. The roll 26 is preferably provided with a rubber-covered surface 26' along its whole length to produce friction and prevent slipping of the cloth thereon. The roller 27 is rotated anti-clockwise as viewed in Fig. 1 and the cloth is wound on over the upper side. The arms 30 are pivoted to a pair of brackets 34 carried by and movable upon the frame bar 4, where they may be spaced apart adjustably, according to the width of the shade to be made, set screws 35 being provided to secure the adjustment. Said brackets 34 and arms 30 together constitute means adjustable for supporting shades of different widths. Each shade is held by said means during the winding, tacking and end-pocket sewing operations. A scale is provided for gaging the spacing of said brackets, said scale preferably being formed upon or carried by the bar 4' as indicated at 36.

Side cutters are provided for trimming the edges of the cloth as it feeds forward. Preferably, for the purpose, a pair of coacting disk blades 37 and 38 are carried by each of said brackets 34. These disks are mounted preferably as shown in Fig. 6, the lower disk 38 being carried by a sleeve 39 journaled in the bracket 34 and also keyed for longitudinal movement upon the shaft 40 as the brackets 34 are moved for readjustment. Said keying also provides for rotating the cutter 38 by means of said shaft 40 which is operatively connected to the driving gear 20 by means of a gear 40'. The cloth and blades 37-38 move in the same general direction at the point of cutting. The upper disk 37 is carried by a sleeve 41 also journaled in the bracket 34 and provided with an end thrust spring 42 arranged to press the disk 37 forward against the coacting disk 38 to insure efficient shearing action. The sleeve 41 is provided with end thrust ball bearings 43.

The creasing and cut-off means are disposed intermediately of the rolls 13 and 26. The creaser comprises the longitudinally

ridged and grooved bed-plate 4' disposed transversely of the path of the cloth and carried by or constituting substantially a part of the frame bar 4, and a reciprocatory device movable longitudinally of the bed-plate and formed to register with the surface thereof, said device being preferably made in the form of a frame 44 having a handle 45 adapted for gripping to reciprocate the same and a pair of closely spaced similar rollers 46 journaled thereto and arranged to follow each other across the path of the shade cloth.

In the form shown in Fig. 1 the bed-plate 4' and coacting rolls are formed to produce three creases adapted to prepare the end of the cloth for folding, as shown in Figs. 7 and 8. The main or right hand portion of each roll as shown in Figs. 1 and 4 is formed with similar flanges 47 and 48 at each end, whereby two similar creases 49 and 50 respectively may be made. At the left end of each roll is provided a detachable creaser member which in Fig. 1 is shown as a flange 51 spaced apart somewhat from the adjacent flange and adapted to fit a groove 52 formed in the bed plate, whereby a third crease 53 may be made facing in the opposite direction from creases 49 and 50.

In the modified form of bed-plate and roll shown in Fig. 4, the detachable member 54 accomplishes substantially the same purpose as flange 51 of Fig. 1, but is shown in a somewhat different shape, corresponding more nearly with that of the main portion 100 of the rollers, and may be secured by any convenient means 55.

When cloth is used which is of the same color on both sides the third-crease attachment 51 is omitted or detached from the creaser rolls, and the shade is creased and folded as in Figs. 7 and 8; but when "duplex" cloth is used having its opposite sides colored differently the attachment 51 is used and the form of pocket shown in Figs. 9 and 10 is produced, whereby the folded or pocket portion will be of the same color as the rest of the shade on each side respectively.

The creaser is held in its operative position and is guided by means of a longitudinal rod 56 secured to the end plates and passing through the handle 45.

A cut-off blade 57 is carried rigidly on the side of the creaser frame toward the feed rolls whereby the successive sections of shade cloth are severed from the main body by the operation of moving the creaser frame forward. By this means the cloth is creased and cut simultaneously by a single movement of the hand of the operator.

In order to provide for drawing the cloth forward automatically after it is cut off and without thereby further feeding cloth through the rolls 13-14 a hand-operated

ratchet clutch 13' is splined on the end of the roll 13 whereby the latter can be thrown into and out of gear with the wheel 22.

Shade cloth affixing means 58 are provided adjacent to the position of the shade-roller 27 preferably adapted for tacking the forward end of the cloth to said roller. The tacking device comprises a frame 59 pivotally mounted on a longitudinally disposed stationary bar 60 and having a part 59' adapted to serve as a handle, and also having means of any desired type (contained in the body 58 but not illustrated) for automatically feeding tacks, staples or other fastening means into place, and also having a hammer or similar striking means 61 adapted for manual operation, a restoring spring 62 being provided by which the hammer is raised after each stroke. The tacking machine when not in use may be swung back, as shown in Fig. 1, against the frame bar 6 and away from the position of the shade-roller, and at all times is freely slidably longitudinally along the bar 60, so as to distribute the tacks or other fastening means along the length of the shade-roller, and to permit removing it to one side when not in use.

The sewing machine 7 is mounted to travel forward and backward longitudinally on the bar 6 adjacent to the roll 26, said machine being adapted to stitch the edge or edges of the pocket formed at the foot of the shade by folding the cloth as creased by the device 5 for the shade-stick 64. Automatic feed means are provided for controlling the movement and operation of the sewing machine, said means comprising a threaded shaft 66 journaled on the frame plates 2 and 3 and having independent driving means at one end comprising a small gear wheel 68 and a large gear wheel 70 coactively engaging therewith, said large wheel having a crank handle 71 adapted for turning by hand. The rotation of said shaft 66 serves both to move the sewing machine along its guide support 6 and also to operate its sewing mechanism. For this purpose the sewing machine is provided with a threaded clutch 72 adapted for releasing and engaging the threads on said shaft whereby the machine may be moved by said shaft, or disconnected and moved independently. A hand wheel or thumb screw 75 is provided and operatively connected for controlling said clutch. A spring 77 tends to hold the clutch open by raising the threaded member 78 away from the threads on the shaft. In order that the shaft 66 may also drive the sewing mechanism a bevel-gear 80 carried by the sewing machine is mounted to slide longitudinally on said shaft as the machine advances, said gear being splined to the shaft by means of a feather key 82 fixed to the gear and slidable in a longitudinal key-

way 83 in the shaft. The gear 80 is operatively connected in any suitable manner as by gears 84 to drive the sewing mechanism.

Means are provided for throwing the indicator feed roll 14 into and out of engagement with the roll 13, said means preferably comprising a lever 85 pivoted at 86 to a rigid bracket 87 depending from the bar 4, and also having pivotal connection to the medial portion of a longitudinally disposed link 88 which in turn at its ends is pivoted to the free arms 89 of the brackets 15. By depressing the handle 90 the roll 14 is raised and thereby thrown out of action and vice versa.

The machine is operated as follows: A bolt of shade cloth is placed on the supply shaft 8. The end of the cloth is then carried upward and threaded diagonally forward and downward between the feed rolls 13 and 14, the upper of said rolls being raised by lever 85 to facilitate introducing the end of the cloth preparatory to the automatic feeding process. Roll 14 is then lowered to its operative position by means of the hand lever 85. The cloth is then advanced by turning the crank 21, the front edge being passed over the creaser plate and between the side cutters, whereby the edges are trimmed, and thence to the upper side of a shade-roller 27 held by the arms 30. The tacking machine is then moved forward over the edge of the shade and the cloth is attached to the shade roller by means of a series of tacks or other fasteners applied by the tacking machine. The tacker is then moved to one side and the proper length of shade cloth is fed forward and wound upon the shade roller by further turning of the crank 21, the length of the cloth delivered to the shade-roller being indicated by the gage 18. Then the feed mechanism is stopped and the combined hem creaser and cross-cutter is drawn forward across the shade cloth, after which said device is moved to one side and the creased portion is folded, ready for sewing. The clutch 13' is then thrown out of gear so that while the trailing end of the shade is being wound the feed mechanism will remain inactive. The shade is then further wound upon the shade-roller and the creased and folded edge is swung over to bring the hem into the path of the sewing machine, which is then operated by turning the crank 71, whereby the machine is caused to advance across the end of the shade and stitch the folded parts together, ready to receive the shade-stick. When "duplex" cloth is used both sides of the pocket are stitched. When a seam is finished, the clutch 72 is thrown out of gear and the sewing machine moved back to one side ready for the next operation. The finished shade, wound upon its roller, is then removed from the arms 30,

another shade roller inserted ready to receive the next shade, and the clutch 13' is thrown into gear, whereupon the operation is repeated. After the cloth is once started through the feed rolls 13-14 the measuring is continuous with the feeding operation. Any desired form of gage may be used but preferably one in which the index arm may be restored to an initial or zero position after each operation.

Although but one specific embodiment of this invention has been herein shown and described, it will be understood that numerous details of the construction shown may be altered or omitted without departing from the spirit of this invention as defined by the following claims.

We claim:

1. A window-shade machine, comprising a frame, in combination with a pair of brackets carried thereby and slidable longitudinally thereon, arms pivoted to said brackets, said arms being adapted and arranged for detachably holding a shade roller adjustably in operative position, a roll journaled upon said frame coactively adjacent to the shade roller when the latter is in its normal operative position, and means for supplying turning power to said roll.
2. A shade machine, comprising a support member, in combination with a pair of brackets carried thereby and movable longitudinally thereon, side cutters arranged in coactive pairs and movable with each of said brackets respectively, and means for supplying turning power to one of the cutters of each pair respectively.
3. In a window shade machine a frame, means for holding the shade roller demountably, a winding roll upon which the shade roller rests, and means for driving said winding roll.
4. In a window shade machine, a frame, upwardly swingable arms formed and arranged for holding the shade roller demountably, a friction winding roll upon which the shade roller rests coactively, and means for driving said winding roll.
5. In a window shade machine, a frame, upwardly swingable pivoted arms formed and arranged for holding the shade roller demountably, a solid roll upon which the shade roller rests, and tacking means disposed at the other side of the shade roller from said roll, said shade roller being sup-

ported substantially rigidly upon said roll when the tacking means is operated.

6. In a window shade machine, a frame, means for holding the shade roller demountably, a winding roll upon which the shade roller rests, and hem sewing means movable longitudinally of and disposed adjacent to said roller holding means and roll for making a shade stick pocket while the shade roller is held as stated. 65

7. In a window shade machine, a frame, means for holding the shade roller demountably, means coacting with the shade roller for drawing the window shade forward and winding the same on the shade roller, and cutting means carried by the roller holding means respectively for trimming the sides of the window shade as it is drawn forward and wound upon the shade roller, the shade roller holding means being adjustable to hold said cutting means spaced apart according to the width of shade to be made and to receive different lengths of shade rollers as may be required. 70

8. In a window shade machine, a frame, means formed and arranged for holding the shade roller demountably, a friction winding roll against which the shade roller bears coactively, said means and friction winding roll being normally urged together for holding the shade roller and winding roll in frictional contact, and means for driving said winding roll. 85

9. In a shade machine, a frame, having mounted thereon means adjustably spaced apart for holding a shade roller and side cutters carried by said means, a winding roll having a friction surface, said roll and the shade roller holding means being disposed adjacently and being urged together, sewing means movable longitudinally of and adjacent to said roll and holding means and parallelly therewith, tacking means also movable longitudinally of said roll and holding means and parallelly therewith, said tacking means being on the other side of the shade roller position from said roll. 90

Signed at Aurora this 18th day of March 1914.
